UNITED STATES PATENT OFFICE.

FRANK H. NORRIS, OF ROBINSON, ILLINOIS.

STUFFING-BOX FOR POLISHED RODS FOR OIL-WELLS.

1,011,236.

Specification of Letters Patent. Patented Dec. 12, 1911.

Application filed September 8, 1911. Serial No. 848,303.

To all whom it may concern:

Be it known that I, FRANK H. NORRIS, a citizen of the United States, residing at Robinson, in the county of Crawford and State 5 of Illinois, have invented new and useful Improvements in Stuffing-Boxes for Polished Rods for Oil-WellS, of which the following is a specification.

This invention relates to stuffing boxes 10 for polished rods for oil wells and consists in certain improvements in the construction thereof as will be hereinafter fully described and pointed out in the claims.

In connection with the pumps for oil 15 wells, a stuffing box is arranged at the top of the well for the polished rod. These have been commonly made of cast iron and more or less difficulty has been experienced with these breaking due to various causes. In the 20 present invention, the outer wall of the stuffing box is formed of a single piece of tubing or pipe and the shoulder for sustaining the packing made by indenting the walls of the tubing or pipe.

25 The invention is illustrated in the accompanying drawings as follows:—

Figure 1 shows a central section through a stuffing box, the packing being compressed by a spring. Fig. 2 a central section of a 30 stuffing box, the packing being compressed by a weight. Fig. 3 a plan view of the structure shown in Fig. 2.

1 marks the wall of the packing. This has the screw threads 2 at its ends to which 35 the tubing may be attached. It is indented at 3 forming a shoulder on which is preferably arranged a bushing 4. A packing 5 is arranged on the bushing and the follower 6 is arranged on the packing. The follower 40 has the shoulder 7. A spring 8 is arranged between the shoulder 7 and the yoke 9. The yoke 9 is perforated at the ends and bolts 11 extend through these perforations and 45 perforations 12 in the yoke 13. The yoke 13 is arranged around the walls 1, the upper end of the wall of the stuffing box being flanged at 14 to retain the yoke 13 in place. The polished rod A extends through the packing in the usual manner.

50 In the alternative construction shown in Figs. 2 and 3, the follower 6 has the projections 6^a on which rests a lever 15. The lever

is pivoted by means of a pin 16 on the ear 13^b extending from the yoke 13^a. A weight 17 is arranged on the lever and exerts pressure on the follower. With this construction, the walls of the stuffing box are of the same size as the tubing or pipe to which it is attached so that it will form a continuation of the tubing. At the same time, it is conveniently formed of wrought metal so as to avoid breaks which have given trouble heretofore.

What I claim as new is:—

1. In a stuffing box for polished rods for oil wells, the combination of a wrought metal cylindrically shaped tube having a shoulder formed by indenting the tube; a packing above the shoulder; and a follower for putting pressure on the packing.

2. In a stuffing box for polished rods for oil wells, the combination of a wrought metal tube having a shoulder formed by indenting the tube; a bushing on the shoulder; a packing on the bushing; and a follower on the packing.

3. In a stuffing box for polished rods for oil wells, the combination of a wrought metal tube having a shoulder formed therein by indenting the tube; a flange arranged on the upper end of the tube; a packing arranged on the shoulder; a follower on the packing; a yoke surrounding the tube and engaging the flange at the upper end of the tube; and means secured to the yoke for exerting pressure on the follower.

4. In a stuffing box for polished rods for oil wells, the combination of a wrought metal tube having a shoulder formed by indenting the tube; a flange at the upper end of the tube; a lower yoke surrounding the tube and engaging the flange; a packing on the shoulder; a follower on the packing; an upper yoke; a spring between the follower and the upper yoke; and a connection between the upper yoke and the lower yoke.

In testimony whereof I have hereunto set my hand in the presence of two subscribing witnesses.

FRANK H. NORRIS.
